CLAIM

The ornamental design for an audio speaker, substantially as shown and described.

DESCRIPTION

FIG. 1 is a perspective view of an audio speaker, showing my new design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines immediately adjacent the shaded areas represent the bounds of the claimed design while all other broken lines are included for the purpose of illustrating portions of the audio speaker; the broken lines form no part of the claimed design.
